Primary Examiner — Rashida C. Walshon(74) Attorney, Agent, or Firm — Kilpatrick Townsend & Stockton LLP(57) CLAIM

The ornamental design for a shoe, as shown and described.

DESCRIPTION

FIG. 1 is a front lateral perspective view of a shoe.

FIG. 2 is a medial side view of the shoe of FIG. 1.

FIG. 3 is a lateral side view of the shoe of FIG. 1.

FIG. 4 is a front view of the shoe of FIG. 1.

FIG. 5 is a rear view of the shoe of FIG. 1.

FIG. 6 is a top view of the shoe of FIG. 1; and,

FIG. 7 is a bottom view of the shoe of FIG. 1.

The broken lines show unclaimed subject matter only and form no part of the claimed design. The pattern on the sole and the associated recessed areas form no part of the claimed design.

1 Claim, 7 Drawing Sheets(56)
